HENRY C. HEISER, OF CLEVELAND, OHIO, ASSIGNOR TO THE ASTRUP COMPANY, OF CLEVELAND, OHIO, A CORPORATION OF OHIO

AWNING ARM ADJUSTER

Application filed July 28, 1928. Serial No. 296,045.

This invention relates to awnings and supports therefor and particularly to that type of supports which are used intermediate the ends of an awning frame to support the front bar thereof and take up its sag so that the awning will present a level lower front edge.

An awning for a store front or the like, as a rule, is made up of canvas wound on a suitable roller secured to the front of the building with the front edge lapped over and attached to an outer bar or rod which has arms of some form extending to and pivoted to the building so that they may swing up and down with the raising and lowering of the awning. These awnings are of some considerable length across the front of the building and supports throughout the length are necessary to prevent undue sagging and to take up the wear and tear upon the canvas or other awning material. These supports have heretofore been made in the form of extensible and collapsible arms usually of pivoted arm parts adapted to fold into small compass with the raising of the awning and to extend themselves by gravity with the lowering of the awning ultimately reaching a supporting position to carry part of the load and prevent sagging. These devices have been capable of adjustment as to their extended position but possess one distinct disadvantage, to wit, that it requires two people to properly adjust the arms and by reason of the upward collapsibility of these arms proper positioning of the outer end becomes difficult.

To avoid the foregoing disadvantage and to improve the utility of these devices the present invention contemplates an adjustment between the supporting bracket and each arm arranged in a manner such that once the bracket and arm are assembled in general supporting arrangement, a single operator adjacent the bracket may adjust the final extended position of the entire arm and thereby not only save time and labor but insure a perfect adjustment of the arms.

The entire invention together with its details is very nicely exemplified in the following description, drawings and claims.

In the drawings, Fig. 1 represents a top plan view of an awning to which a pair of

arms is applied with parts broken away to show the various features; Fig. 2 is a section upon the line 2-2, Fig. 1; Fig. 3 is a section upon the line 3-3, Fig. 1, looking in the direction of the arrows; and Fig. 4 is a section upon the line 4-4, Fig. 3. 55

In the embodiment disclosed in the drawings, 1 represents a suitable building front or wall provided with the roller brackets 2 for receiving the awning roller 3 upon which the awning 4 may be wound. This awning has the usual front skirt 5 and the usual heading or envelope 6 for receiving the front bar 7 which extends the full length of the awning. 60

Secured to the building front or wall 1 is a suitable arm support or wall bracket comprising a base plate 8 and an outwardly extending plate member 9 having an opening for receiving an arm bolt 10 and slot 11 through its web concentric with the axis of the bolt 10. Engaging the bolt 10 is a bearing bracket or bearing support 12 of U-shaped form as shown in Fig. 4 and providing upper and lower bearings 13 adapted to receive a suitable pivot pin 14. Upon the pin is pivoted an inner arm rear bracket 15 secured to upper and lower arm rails 16 extending out and provided with a forward arm bracket 17 provided with upper and lower lateral ears 18 receiving an intermediate pivot pin 19. These ears 18 engage above and below a front arm rear bracket 20 pivoted upon the pin 19. Extending from this front arm rear bracket is an outer arm 21 carrying an outer eye 22 extending around the rod 7. In the arrangement shown in Fig. 1 there are two of these supporting arms. The inner arm rear bracket has a web provided with a single opening 23 for the reception of a bolt 24 adapted to pass through it and through the slot 11 for holding the parts in clamped relation and in final position. 70 75 80 85 90

So far the description has been confined to that which is old and well known in the art 95 and the specification will now proceed with the improved construction.

Referring to Fig. 3 it will be seen that the plate member 9 is provided with a downwardly extending ear 25 and the bearing 100

bracket 12 is also provided with an ear 26 for receiving the bent end portion 27 of an adjusting rod or bolt 28 passing through the ear 25. The bent end portion 27 is provided with a suitable nut 29 for holding it in place. The adjusting rod 28 is threaded and receives adjusting nuts 30 arranged on each side of the ear 25.

In use the operative secures the supporting bracket to the building front or wall and then proceeds to connect to it the assembled collapsible arm by inserting the bolt 14, taking care to see to it that the adjusting rod 28 passes through the ear 25 and that one of the nuts 30 is on either side of this ear. When he wishes to adjust the front end of the collapsible arm he does so by manipulating the nuts 30 which results in the arm being swung to different angular positions with respect to the building front or wall. When the proper adjustment at this point has been made the bolt 24 may be drawn up and the parts clamped in this position.

It will be seen from the foregoing that not only is the adjustment of the supporting arms accomplished by a single operative at the building front but a more correct adjustment of these arms is possible by the improvement disclosed in this application by reason of the fact that the arms are not being held up at their outer ends but are permitted to extend themselves freely and evenly and without hindrance to their natural extended position with the adjustment made while in this condition. This results in a better and more effective job throughout.

Having described my invention, I claim:

1. In combination, an awning lateral arm, a bearing support, means for swingingly mounting said lateral arm on said bearing support, means for pivotally mounting said bearing support, an adjusting bolt pivotally connected with said bearing support for effecting movement thereof about its pivot and for holding said bearing support in any desired position to which it is moved, a stationary member through which said bolt extends, and means for adjustably connecting said bolt with said stationary member.

2. In combination, an awning lateral arm, a bearing support, means for swingingly mounting said lateral arm on said bearing support, a wall bracket, means for pivotally mounting said bearing support on said wall bracket, an adjusting bolt pivotally connected with said bearing support for effecting movement thereof about its pivot and for holding said bearing support in any desired position to which it is moved, means carried by said wall bracket through which said bolt extends, and means for adjustably connecting said bolt with said means carried by said wall bracket.

3. In combination, an awning lateral arm, a bearing support, means for swingingly

mounting said lateral arm on said bearing support, a wall bracket having an arcuate slot, a bolt carried by said bearing support and extending through the arcuate slot of said wall bracket, means for pivotally mounting said bearing support on said wall bracket, an adjusting bolt pivotally connected with said bearing support for effecting movement thereof about its pivot and for holding said bearing support in any desired position to which it is moved, means carried by said wall bracket through which said bolt extends, and means for adjustably connecting said adjusting bolt with said means carried by said wall bracket.

4. An awning lateral arm mounting, comprising a wall bracket, a bearing support pivotally mounted on said wall bracket and adapted to swingingly support the inner end of an awning lateral arm, positive means connected to said wall bracket for adjusting said bearing support about its pivot, and means associated with said positive means for locking said bearing support in any desired position of adjustment.

5. In combination, an awning lateral arm, a bearing support, means for swingingly mounting said lateral arm on said bearing support, a wall bracket, means for pivotally mounting said bearing support on said wall bracket, positive means for adjusting said bearing support about its pivot, and locking means on said positive means for locking said bearing support in any desired position of adjustment.

6. An awning lateral arm mounting, comprising a wall bracket means, a bearing support means pivotally mounted on said wall bracket means and adapted to swingingly support the inner end of an awning lateral arm, and an adjusting bolt having connection with said wall bracket means and said bearing support means, the connection of said bolt to one of said means being an adjustable one, whereby said means can be adjusted relative to said other means.

In testimony whereof I hereby affix my signature.

HENRY C. HEISER.
